(57) **CLAIM**

The ornamental design for a LED light, as shown and described.

DESCRIPTION

FIG. 1 is a perspective view of a LED light according to our new design;

FIG. 2 is a right side view thereof;

FIG. 3 is a left side view thereof;

FIG. 4 is front view thereof;

FIG. 4A is an enlarged front view thereof;

FIG. 5 is a rear view thereof;

FIG. 5A is an enlarged rear view thereof;

FIG. 6 is a top view thereof;

FIG. 7 is a bottom view thereof; and,

FIG. 8 is an enlarged perspective view showing a rear fragment thereof taken along line 8-8 FIG. 1.

The wavy line in FIG. 8 indicates the boundary of the fragmented figure and forms no part of the claimed design.
